UNITED STATES PATENT OFFICE

VLADIMIRE J. OBIDINE, OF LOS ANGELES, CALIFORNIA

FACE-STEAMING APPLIANCE

Application filed August 28, 1929. Serial No. 388,947.

My invention is a face steaming appliance in which the steam is generated in the appliance itself, such appliance being fitted over a person's face.

5 An object of my invention is a face steaming device which may be placed over the face, in the form of a mask and has integrally connected therewith, a steam generating device so that the steam when generated comes 10 in contact with the skin of a person's face and thus gives the functions of steaming the face such as in softening the beard for men and also as a face steaming appliance suitable 15 for women in beautifying or treatment of the face.

Another object of my invention is a mask-like device in which the steam is generated in the mask itself and such mask is adapted to be worn over the face and by which medicated vapors may be discharged from the steaming device and inhaled either through 20 the nose or mouth, this being used for medicinal purposes, either for men or women.

A still further object of my invention is 25 the use of preferably an electric heater for generating steam, in which the flow of water to the generator may be graduated to flow drop by drop and therefore the amount of steam generated may be readily controlled, 30 the wearer of the mask thus has control of the rate at which the steam is developed and of the intensity of the application of the hot vapors to the skin of the face, or in medicinal treatments to the inhaling of the medicinal 35 properties of the vapor.

A still further object of my invention is 40 the construction of an appliance in several forms such as a mask which may be worn over the chin, extending to a close fit at the neck and extending at the side of the face, front of the ears and under the nose. This is suitable for the use of men in softening their beards preparatory to shaving. For 45 the use of barbers to soften the beard or for a face massage I provide another form of mask which is adapted for use on a person when in the recumbent position. This has preferably two steam generators, one on each side of the face, the mask preferably covering 50 from underneath the chin close to the

neck to above the eyebrows and having a nose or mouth breathing arrangement.

Another object of my invention in a mask-like form of device to cover the major portion of a person's face, is in employing a 55 breathing opening which may surround the nose and allow breathing of fresh air without breathing the steam, or another arrangement by which a rubber nipple may be gripped by the mouth and allow breathing through 60 the mouth, this being adapted particularly for medicinal treatments in which the wearer may breath unmedicated air when the medicated vapors are found to be objectionable. The design of appliance for use for medicated 65 vapors preferably encloses the major portion of the face, reaching from below the chin to above the eyebrows and on both sides well back to the ears.

My invention is illustrated in the accompanying drawings, in which

Figure 1 is a front elevation of the general form of mask, showing this in the position when worn;

Fig. 2 is a side elevation partly broken 75 away of the mask of Fig. 1;

Fig. 3 is a side elevation partly broken 80 away of a modification of the full face mask, having an opening for the nose, for breathing;

Fig. 4 is a modification of the construction 85 of Fig. 3, having a breathing aperture for the mouth;

Fig. 5 is a side elevation partly broken 90 away, of a steaming appliance for use when a person is in the recumbent position;

Fig. 6 is a view of the device of Fig. 5, taken in the direction of the arrow 6;

Fig. 7 is a vertical section through one 95 form of steam generator;

Fig. 8 is a section on the line 8-8 of Fig. 7, in the direction of the arrows;

Fig. 9 is a section on the line 9-9 of Fig. 7 in the direction of the arrows;

Figs. 10 and 11 are a plan and section 95 respectively of an alternative form of heater.

Referring first to the construction shown in Figs. 1 and 2, this illustrates a mask 11 which is formed with a front wall 12, a rear wall 13, a lower end connection 14 and side 100

walls 15. The side walls extend considerably higher than the front and rear walls, there being an opening 16 at the back which fits underneath the chin and an opening 17 at the front which fits over the upper lip underneath the nose. The mask has a rim 18 extending over the top of the sides and around the chin fitting and nose fitting portions of the nose. This rim preferably has a bead 19 formed of rubber or the like with a rubber flap 20 to engage the face and form a more or less steam-tight connection. A series of openings 21 are provided at the top of the sides for the escape of steam and in order to secure the mask to the head, an eye 22 is secured to the upper end of the sides and has straps 23 which extend over the head. These straps are adjustable in order to adjust the device to different size heads.

The steaming device comprises a steam generator designated generally by the numeral 24 which generator is illustrated as being electrically heated, the current being conducted to the generator by a flexible cable 24'. The water is fed to the steam generator from a reservoir 25 which is molded to the front wall of the mask. This reservoir has a filling cap 26 and the outlet is controlled by a valve 27 having a valve stem 28 with a knurled knob. The water is adapted to discharge from the reservoir through a small pipe 29.

A satisfactory form of steam generator is formed with a cylindrical wall 30 having a flange 30' at the bottom with a depending structure 31 through which extends the electric cables or cords 24'. A switch housing 32 is mounted on the flange 30' and has two switches controlled by movable buttons 33. These are of a conventional type and each controls a circuit to inner and outer electric heating coils 34 and 35 imbedded in porcelain or equivalent insulator 36. Above the coils is a pan 37 into which the water drips from the discharge nozzle 38 leading from the pipe 29 through the cover 39 and the cap 40. The upper portion of the pan is provided with a series of perforations 41 and surrounding the upper portion of the cylindrical structure 29 there are a series of steam openings 42. The cylindrical structure has a flange 43 by which it may be connected through the bottom of the mask.

With this construction of the appliance, the person using it may place the mask on the face and this encloses the chin, the sides of the face and the upper lip. The heat may be turned on either one or both of the coils, these being designed to give a low, medium and high heat and as the water is allowed to drip from the reservoir drop by drop into the pan, this is evaporated and turned into steam substantially immediately. One of the coils may be for low heat, the other coil for an-

other temperature and the two coils together would give the high heat. The steam being injected through the holes 42 flows up the sides of the face, up the chin and also steams the underside of the chin, thus an effective 70 steaming may be obtained to soften the beard for purpose of shaving and while the mask is being worn the party using same may prepare his shaving utensils so that the device materially facilitates home shaving in that 75 the steaming device effectively softens the beard before application of the soap to make a lather. The device may also be used after shaving to relieve any skin tension or soreness due to shaving of stiff beards or the like. 80

The device of Figs. 5 and 6 is particularly adapted for use in barber shops and in this case the mask 44 is constructed having a bottom edge 45 to accommodate the chin, a top edge 46 to engage the forehead and depending side edges 47 to fit against the side of the face. This type of mask is provided with an enlarged breathing tube 48 which is adapted to allow breathing through the nose, the tube having a relatively tight fit against the upper lip and around the nose. The tube is held expanded and pressed against the face by the coil spring 49. In this construction there are two depending structures 50 on each side, each having an electric steam generating unit 51. Each of these is provided with an electric heater with the pan and each with a separate reservoir independently controllable. By this construction the barber may start the appliance generating steam and the person to be shaved by controlling the valves on each side, may regulate the amount of steam being applied to the face, thus preventing too high a temperature which might cause a species of burn, but still heating and moistening the beard. After shaving the barber may apply the mask again to steam the face. 95

In the construction of Fig. 3, the mask 52 is constructed with a rim fitting under the chin as indicated at 53 and against the forehead as indicated at 54, the sides fitting against the sides of the face close to the ears as indicated at 55. This has a steam generator 56 which may be of the same general type as illustrated in the prior figures. It is provided with a nose breathing enlarged tube 57 expanded by a spring 58 and pressed against the face. This type is of considerable use in steaming the whole of the face and allowing the person to breathe freely through the nose. 110

In Fig. 4 the mask 59 is of the same general character and construction as shown in Fig. 3. It is provided with a breathing tube 60 which preferably has a rubber nipple 61 on the end which may be placed in the mouth so that the person using the device may breathe through the mouth when they desire fresh air or breathe through the nose. 120

when desiring to breathe medicated air. The device of Figs. 3 and 4 are particularly adapted to steam the whole face as well as for use in breathing medicated vapors. The device of Fig. 3 is particularly adapted for breathing medicated vapors through the mouth and fresh air through the nose and the device of Fig. 4 is particularly adapted for breathing medicated vapors through the nose and fresh air through the mouth. In both of these constructions the generation of steam may be controlled by the person using the device, by controlling the valve and the electric heat.

15 In order to provide a flow of air through the device as well as steam, the depending structure 31 of the steam generator is provided with a series of apertures 62 and the metal plate 63 supporting the porcelain insulator 36 also has a series of openings 64. A certain amount of air therefore can circulate through the apertures 62, 64 and 41 in the pan passing out with the steam through the openings 42 into the interior of the mask.

25 In Figs. 10 and 11 I show an alternative form of heater using a pan 65 similar to the pan in the construction of Fig. 7 and on the top of this pan I have a heating coil 66 which is formed of a metal tube 67 having a heating wire 68 threaded thereto, the wire being insulated from the metal of the tube. With this construction the tube is heated by the current passing through the wire and the water drops into the pan and possibly some on the tube itself. This allows a simpler construction of mounting for the pan. The heating elements may be arranged to give a plurality of different degrees of temperature.

In order to control the flow of air through the mask and the escape of steam, I provide a control valve designated generally by the numeral 70, in the side of the mask. This valve has an angular plate 71 having its lower corner pivoted on a stud 72, which stud 40 may be one of those used to support the eye 22. The valve is provided with a series of apertures 73 which are adapted to align with the openings 21 in the sides of the mask or to be positioned between these openings or any 45 desired degree of opening. The movement of the plate is controlled by a stud 74 extending from the plate through a slot 75 in the upper part of the side of the mask. This valve at the top controls mainly the overflow 50 of the steam and also the heated air which rises upwardly in the mask.

In addition to controlling the flow of air into the bottom of the mask, I provide a slip ring 76 fitting in the bottom of the steam generator, preferably resting on the plate forming the depending structure 31 having the aperture 62. This slip ring has a series of apertures 76' and may be partly rotated by the stud 77 which projects through a slot in 60 the depending structure 31. By shifting the

stud, the ring 76 may be slipped in a rotary manner so that the apertures 62 may be made to align with the apertures 76' or to be out of register therewith or in any intermediary position. This construction gives control of the flow of air into the mask. 70

An important characteristic of my invention is in the feature of the water reservoir being enclosed and attached in a fixed position relative to the steam generator and having a control valve whereby water may be allowed to drop into the steam generator drop by drop, which generator may be heated to such a temperature that the water is immediately turned into steam. Thus a person may use my face mask with a steam generator in a recumbent position. There is no danger of having the water overflow and wet the person's clothing. The small amount of air which is necessary to enter the water reservoir may be allowed to flow in by having the cap 26 sufficiently loose to allow slight passage of air. 80

85 Another important feature and characteristic of my invention is that the air for ventilation purposes is intermingled directly with the steam and the flow of such air is readily regulated. This prevents jets of hot steam from striking any particular part of a person's face, but they are able to have a 90 distributed moist heat. 95

Various changes may be made in the principles of my invention without departing from the spirit thereof as set forth in the description, drawings and claims. 100

I claim:

1. A device as described, comprising in combination a mask-like device adapted to cover part of a person's face, a steam generator at the bottom of the mask having a 105 pan, electric heating units and means to circulate air upwardly into the mask through the steam generator, a closed reservoir connected to one side of the mask on the inside and having a filler opening with a cover on the outside, a valve connected to the outlet from the reservoir and having a control element outside of the mask, means to drop water after passing the valve into the pan and a suspending means to attach the mask to a 110 person's head. 115

2. A device as described, comprising in combination a mask-like device adapted to enclose at least part of a person's face and having a steam generator connected to the 120 bottom, said generator having a tubular structure attached to the bottom of the mask, an electric heating unit in said structure, a pan above the steam generator, air passages through the bottom to the pan, there being a 125 series of openings in the upper part of the structure communicating between the interior of the steam generator and the inside of the mask, a closed water reservoir connected to one side of the mask and having a filling 130

opening with a cap on the outside, a valve controlling the flow of water from the reservoir, and means to lead the water from the valve to the pan.

3. A device as described, comprising in combination a mask-like structure adapted to engage a person's skin, a steam generator connected to the mask, a closed water reservoir connected to the mask and with a filling opening

10 with a closure outside of the mask, a valve having a control for the water from the reservoir to the generator, electric heating units for the generator, and a ventilating structure connected to the generator whereby fresh air

15 intermingles with the steam in the generator.

4. A device as described, comprising a mask-like structure having edge portions to engage under a person's chin, the side of the face and the upper lip under the nose, a steam

20 generator mounted in the bottom of the mask, a closed water reservoir secured to one side of the mask and having a filling opening with a closure cap on the outside of the mask,

25 a valve connecting the reservoir and the generator with an operating stem extending outside of the mask, and electric heating units for the steam generator.

5. In a device as described, a structure connected to a mask and having a steam generator in the bottom, said generator having a peripheral wall, a water pan connected thereto having marginal openings, an electric heating unit below the pan, a closed reservoir connected to the structure, means to drip

35 water from the reservoir on to the pan, the wall of the steam generator having ventilating openings above the pan for outlet of steam and air into the mask and a controllable means to pass air through the openings in the pan.

40 6. A device as described comprising a mask-like device adapted to enclose at least part of a person's face, the said mask having an edge to contact with the face, a steam generator attached to the bottom of the mask and being

45 movable therewith, a closed water reservoir attached to one side of the mask and having a control valve to regulate the flow of water from the reservoir to the generator, and means to circulate air from the bottom of the mask upwardly inside of such mask.

50 7. A device as described comprising in combination a mask-like device having an edge to fit under a person's chin, two edges to extend upwardly over the sides of the face, means to

55 attach the mask to the head, enclosing at least the chin, a steam generator in the bottom of the mask having an electric heater, a closed water reservoir attached to the mask and having a filling opening on the outside, and means

60 extending outwardly from the mask to control the flow of water from the reservoir to the generator.

8. A device as described comprising in combination a mask-like device adapted to enclose at least part of a person's face and hav-

ing a steam generator, a closed water reservoir attached to the mask and having a filling opening, means to flow water under control from the reservoir to the generator, the generator having holes to discharge steam into the mask, and means to flow air in the said holes from the mask.

In testimony whereof I have signed my name to this specification.
